(57) **CLAIM**

We claim the ornamental design for a handheld acne treatment wand, as shown and described.

DESCRIPTION

FIG. 1 is a perspective view of the ornamental design of the handheld acne treatment wand of our invention;

FIG. 2 is the left side view of the handheld acne treatment wand of FIG. 1;

FIG. 3 is the front view of the handheld acne treatment wand of FIG. 1;

FIG. 4 is the right side view of the handheld acne treatment wand of FIG. 1;

FIG. 5 is the top view of the handheld acne treatment wand of FIG. 1; and,

FIG. 6 is the bottom view of the handheld acne treatment wand of FIG. 1.

The broken lines show portions of the handheld acne treatment wand that form no part of the claims design.
